United States Patent Office

Des. 193,361
Patented Aug. 7, 1962

193,361

JUG

Clifford G. Baker and Carl E. Guldberg, Ann Arbor, Mich., assignors to Plas-Tainer Inc., Saline, Mich., a corporation of Michigan

Filed May 19, 1961, Ser. No. 65,247

Term of patent 14 years

(Cl. D58—5)

FIG. 1 is an elevational view of a jug, showing our new design;

FIG. 2 is an elevational view thereof taken from the left or right of FIG. 1; and

FIG. 3 is a top plan view thereof.

The dominant features of our design reside in the portions shown in full lines.

We claim:

The ornamental design for a jug, substantially as shown and described.
